Patented July 2, 1918.

UNITED STATES PATENT OFFICE.

WILLIAM R. JEAVONS AND ARNOLD R. WHITTAKER, OF CLEVELAND, OHIO.

OIL-STOVE.

1,271,169.

Specification of Letters Patent.

Patented July 2, 1918.

Application filed August 4, 1914 Serial No. 855,045.

To all whom it may concern:

Be it known that we, (1) WILLIAM R. JEAVONS, (2) ARNOLD R. WHITTAKER, citizens of the United States, residing at Cleveland, in the county of Cuyahoga and State of Ohio, have invented certain new and useful Improvements in Oil-Stoves, of which the following is a full, clear, and exact description, reference being had to the accompanying drawings.

This invention relates to burners, and more particularly to the burners of oil heating stoves wherein a wick is employed. The invention, more specifically, resides in a novel construction of gallery and in certain coöperating features of construction of the gallery, the wick tubes, and the heating drum which is located above the gallery and the burner. Further and more limited objects of the invention will appear hereinafter in connection with the detailed description of the parts illustrated in the drawing.

Referring to the drawing forming part hereof, Figure 1 represents a view, partly in section and partly in elevation, of an oil heater of the type known to the trade as "smokeless heaters"; and Fig. 2 is a view, partly in section and partly in perspective of the gallery which is employed in connection with said heater.

The heater illustrated herein is of the type wherein wick tubes project upwardly from the central portion of a reservoir, which is mounted within a stove base or base ring, the stove drum being hinged to the stove base through an extended bottom or "cone plate" which is open at the center to admit the upper end of the air distributor and the flame burning from the top of the wick, there being a collar depending from the central opening of this plate and adapted to engage the top of the gallery, which is preferably mounted on top of the reservoir and surrounds the outer wick tube.

It has been found desirable to make the gallery easily removable and to provide it with an inwardly projecting trough which is adapted to substantially contact with the outer wick tube, whereby any particles falling in the space between the outside of the outer wick tube and the gallery may be caught and retained until such time as it is desired to remove the gallery, when the particles or other material may be conveniently removed from the gallery by merely invert-

ing the same. Among the particles thus liable to fall within this space and accumulate on top of the reservoir are the carbonized portions of the wick which are liberated in considerable quantity whenever the top of the wick is rubbed to even and clean the same. However, it frequently happens that the operator, in replacing a gallery having the trough referred to, will invert the gallery, with the result that the inwardly projecting trough will block the flow of air through the perforations of the gallery then therebeneath to the exterior of the flame, resulting in imperfect combustion, with consequent evolution of smoke and the possibilities of even more serious consequences. It is a further object of this invention to provide a gallery construction which is applicable to a stove of the type referred to, which will secure the advantages referred to and which, should the operator invert the same, will (obviously to the operator) prevent the stove drum from occupying a proper relation to the parts therebeneath and particularly will prevent the engagement of the latch members which fasten the drum until the gallery is placed in its proper position.

In the drawing forming part hereof, 1 denotes the stove base, the same being shown as a ring having legs 2 and having suitable means, as inwardly projecting segmental flanges 3, for supporting the reservoir 4. Although the reservoir may be supported in any approved manner within the stove base, we have shown the top of the reservoir as provided with a flange 5 which is adapted to be supported by upwardly projecting bosses 6 on the segmental flanges 3— a construction described and claimed in our copending application No. 855,044, filed August 4, 1914.

The reservoir is of the type shown in the aforesaid application, being shallow and having an extended substantially horizontal top 7. The reservoir is provided with a central opening for the outer wick tube 8 and the inner wick tube 9. These tubes preferably extend completely through the reservoir and project above and below the same, and the bottom may be provided with a wind shield 9a such as shown in the application of Wm. R. Jeavons No. 782,005, filed July 30, 1913.

Projecting upwardly from the top of the inner wick tube is the air distributor 10,

which may be of any approved type, such, for instance, as disclosed in the patent to Wm. R. Jeavons No. 906,887. Above the reservoir is located the drum 11, said drum 5 being secured to a bottom or "cone plate" 12, the portion of which within the drum is of frusto-conical shape and is provided with a central opening. The portion of the cone plate outside of the drum projects downwardly and is adapted to seat within a bead 1^a at the top of the stove base, to which base it is hinged, the hinge being indicated generally at 13. Opposite the hinge, the base 1 and the cone plate are provided with 10 coöperating latch members 14 and 15 respectively which, when the cone plate is in proper relation to the reservoir and burner (in this case, resting within the bead 1^a), will be in operative relation to each other 15 to retain the drum closed.

From the central opening in the cone plate there depends a collar 16. The body of this collar is substantially cylindrical, but is provided at its lower end with an outwardly 25 flaring skirt comprising an outwardly projecting portion 17, a downwardly projecting portion 18, and an outwardly and downwardly flaring portion 19. This skirt co-operates with the top of the gallery, which 30 will now be described:—

The top of the reservoir, adjacent to the wick tube 8, is formed into a substantially horizontal annulus, indicated at 20, and the metal of the reservoir bounding the outer 35 edge of this annulus is preferably inclined outwardly, as shown at 21. The gallery which we employ comprises a substantially cylindrical wall 22, the upper edge whereof is bent outwardly and downwardly to form 40 an inverted U, as shown at 23. The metal forming the bottom portion of the cylindrical wall is bent outwardly and downwardly to provide a flange 24, which may be of the same inclination as the inclined surface 45 21. A sheet metal annulus is connected to the flange 24 by having its outer edge portion bent therearound, as shown at 24^a, the bottom of the outer portion of said annulus contacting with the flange 24, as 50 shown at 24^b. The annulus extends horizontally inwardly from the bottom of the wall 22, forming a bottom 25 for the trough (to be described hereinafter) and a means for supporting the gallery assembly on top 55 of the surface 20 of the reservoir. The inner portion of the annulus is shown as bent inwardly and upwardly at 26 and thence upwardly at 26^a to provide a vertical flange adapted to contact with the outer wick tube. 60 The outer vertical wall 22 of the gallery is perforated, as indicated at 22^a, from a point above the bottom to a point somewhat below the top. This provides, within the bottom of the gallery, a trough the top of 65 which is defined by the top of the flange 26^a

and the bottom row of perforations in the wall 22.

The parts will be so constructed that the gallery will be practically centered by means of the engagement of the inner edge of the flange 26^a with the outer wick tube, and the parts will be so proportioned that, when the drum is swung downwardly upon its hinge and latched to the stove base, the top of the gallery will be in substantial engagement with the outwardly projecting flange 17 of the collar 16. It will be evident that any matter that may drop within the space between the vertical wall 22 of the gallery and the outer wick tube will be collected within the inwardly projecting trough carried by and forming part of the gallery. It will also be evident that, when the drum is unlatched and swung back upon its hinge, the gallery may be lifted from its seat, the matter within the trough removed, and the gallery conveniently replaced.

In the event that the operator should invert the gallery, it will be evident that the inwardly projecting trough will then extend above the perforations in the gallery and will block the flow of air through these perforations to the outer portion of the flame, with corresponding detriment to the combustion and the possibility of serious 95 consequences. To prevent the stove from being operated with the gallery thus inverted, the outwardly projecting flange is provided. Through the provision of this flange (which is laterally extended to prevent it from entering the skirt which depends from the collar 16) it will be impossible for the operator to close the drum, the flange engaging the collar and preventing the drum from closing to an extent that will permit 100 the latch member to coöperate. Only by removing the gallery and placing it in proper position can the drum be closed. In other words, as long as it is possible to close the drum, the operator will know that 105 the gallery is in proper position to perform its usual functions and the additional functions due to its peculiar construction and environment; when it is impossible to close the drum, the operator will know that the 110 gallery has been inverted and will have to remove it and restore it to proper position before the stove can be operated.

The depending skirt 18 forms in effect a telescopic connection with the top of the gallery 22. This accommodates any irregularity that may arise through imperfect assembling of the parts; it also accommodates variations in the positions of the bottom of the collar and the top of the gallery, 125 due to the expansion and contraction of the cone plate by which the collar is carried. When this plate expands, through the heating operation, the tendency is to elevate the collar. The telescoping connection between 130

the collar and the top of the gallery accommodates this expansion without interfering with the proper function of the parts, preserving a substantially air-excluding joint 5 between the collar and the gallery notwithstanding variations in the vertical position of the bottom of the skirt with reference to the top of the gallery.

We have shown the drum as provided 10 with an outwardly and upwardly inclined shield 27 of the type set forth and claimed in our application No. 855,044. We have also shown and described other details relating to the reservoir, the stove base, and 15 certain other parts. These, however, may be varied or departed from as desirable, but without affecting the invention covered hereby; and we do not propose to be limited to such details of construction except as they 20 may be positively included in the claims hereto annexed or their inclusion may be rendered necessary by the prior state of the art.

Having thus described our invention, 25 what we claim is:—

1. In a stove of the character described, the combination of a reservoir, an inner and an outer wick tube projecting above the same, a drum pivotally supported with respect to said reservoir, a gallery removably mounted about the outer wick tube, a collar depending from the drum and adapted to engage the top of the gallery, and means holding the drum out of operative relation 35 to the parts therebeneath in the event that the gallery is inverted.

2. In a stove of the character described, the combination of a reservoir, an inner and an outer wick tube projecting thereabove, a 40 drum movable with respect to said reservoir and having an annular bottom plate, a pair of latch members for holding the drum in operative relation to the reservoir and wick tubes, a gallery removably mounted about the outer wick tube, a collar depending from the opening in the bottom plate coöoperating with the top of the gallery, and means whereby the latch members are kept out of engagement in the event that the gallery is 45 inverted.

3. In a stove of the character described, the combination of a reservoir, an inner and an outer wick tube projecting above the same, a drum pivotally supported with respect to the reservoir, a pair of latch members adapted to secure the drum in closed position above the reservoir, a removable gallery mounted outside the outer wick tube, an annular bottom plate for the drum having a central opening, a collar depending from said central opening and adapted to substantially engage the top of the gallery when the drum is latched, and a projection on the bottom of the gallery which, when 55 the gallery is inverted, is adapted to engage

the said collar before the latch members are in operative relation to each other.

4. In a stove of the character described, the combination of a reservoir, an inner and an outer wick tube projecting above the same, 70 a drum movable with respect to the reservoir, a pair of latch members adapted to secure the drum in closed position above the reservoir, a removable gallery mounted about the outer wick tube, a collar carried by the drum and adapted to substantially engage the top of the gallery when the drum is latched, and a projection on the bottom of the gallery which, when the gallery is inverted, is adapted to engage the said collar 75 before the latch members are in operative relation to each other.

5. In a stove of the character described, the combination of a reservoir, an inner and an outer wick tube projecting above the 80 reservoir, a drum pivotally supported with respect to the reservoir, latch members for securing the drum in closed position above the reservoir, the drum being provided with an annular bottom plate having an opening, 85 a collar depending from the said opening and having at its lower end a depending skirt of greater diameter than the body of the collar, a gallery removably mounted about the outer wick tube and having an 90 upper end of a diameter to be overhung by said skirt and having at its bottom an outwardly projecting flange of greater diameter than the inner diameter of said skirt whereby the latch members cannot be engaged in the event that the gallery is inverted.

6. In a stove of the character described, the combination of a reservoir, an inner and an outer wick tube projecting above the reservoir, 105 a drum pivotally supported with respect to the reservoir, latch members for securing the drum in closed position above the reservoir, the drum being provided with an annular bottom plate having an opening, a 110 collar depending from the said opening and having at its lower end an outwardly projecting skirt, a gallery removably mounted about the outer wick tube and having an upper end of a diameter to be overhung by 115 said skirt and having its bottom of greater diameter than the inner diameter of said skirt whereby the latch members cannot be engaged in the event that the gallery is inverted.

7. In an oil stove, the combination of a reservoir, an inner and an outer wick tube projecting thereabove, a drum pivotally mounted with respect to the reservoir and having an annular bottom plate, a collar depending from the opening in said plate, a pair of latch members for securing the drum in operative relation to the reservoir, a gallery removably mounted about the outer wick tube and having at its bottom an inwardly pro- 120

jecting trough, and coöperating means carried by the gallery and the collar whereby the latch members are kept out of operative relation to each other in the event that the gallery is inverted.

8. In an oil stove, the combination of a reservoir, an inner and an outer wick tube projecting thereabove, a drum pivotally mounted with respect to the reservoir, a collar depending from the drum, a gallery removably mounted about the outer wick tube and having at its bottom an inwardly projecting plate, and coöperating means carried by the gallery and the collar whereby the drum is held out of operative relation to the parts therebeneath should the gallery be inverted.

9. In an oil stove, the combination of a reservoir having an inner and an outer wick tube, a drum pivotally mounted with respect to said reservoir, a pair of latch members adapted to retain the drum in operative relation to the reservoir and wick tubes, an annular bottom plate for the drum, a collar depending from the central opening in said plate and having at its bottom a depending skirt of greater diameter than the body of the collar, and a gallery removably mounted about the outer wick tube and having an inwardly projecting trough at its bottom the inner periphery whereof is adapted to engage the outer wick tube, the upper end of said gallery being of a diameter to fit within the depending skirt of the collar and the bottom of the gallery having an outwardly projecting flange of greater diameter than the inner diameter of said skirt.

10. In an oil stove, the combination of a reservoir having an inner and an outer wick tube, a drum pivotally mounted with respect to said reservoir, a collar depending from the drum, and a gallery removably mounted about the outer wick tube and having an inwardly projecting bottom plate, the upper end of said gallery being of a diameter to coöperate with said collar and the bottom of the gallery having a projection adapted to engage the collar when the gallery is inverted and hold the drum out of operative relation to the parts therebeneath.

11. In an oil stove, the combination of a reservoir, an inner and an outer wick tube projecting thereabove, a drum pivotally supported with respect to the reservoir, latch members for securing the drum in operative relation to the wick tubes and the reservoir, an annular bottom plate within the lower portion of the drum, a collar depending from the central aperture of said plate, said collar having at its bottom an outwardly projecting flange and a skirt depending from said flange, a gallery removably supported about the outer wick tube and having its vertically extending wall perforated, the perforated area being located above the

bottom of the gallery to provide an imperforate portion therebeneath and the gallery having at the bottom an outwardly projecting flange of greater diameter than the inner diameter of the skirt and an inwardly projecting wall or flange having its inner edge projected upwardly and adapted to engage the outer wick tube and to form with the bottom and the imperforate part of the outer wall of the gallery a trough, the upper end of the gallery being of a diameter to be received within the depending skirt of the collar.

12. In an oil stove, the combination of a reservoir, an inner and an outer wick tube projecting thereabove, a drum pivotally supported with respect to the reservoir, latch members for securing the drum in operative relation to the wick tubes and the reservoir, an annular bottom plate within the lower portion of the drum, a collar depending from the central aperture of said plate, a gallery removably supported on top of the reservoir and having its vertically extending wall perforated, the perforated area being located above the bottom of the gallery to provide an imperforate portion therebeneath and the bottom of the gallery being provided with an inwardly projecting wall or flange having its inner edge adapted to substantially engage the outer wick tube and to form with the bottom and the imperforated portion of the outer wall of the gallery a trough, the upper end of the gallery coöperating with the collar to control the supply of air to the outer portion of the flame, and means carried by the collar and the gallery and adapted to engage each other to hold the drum out of operative relation to the parts therebeneath should the gallery be inverted.

13. In an oil stove, the combination of a reservoir, an inner and an outer wick tube projecting thereabove, a drum movable toward and from the reservoir, means for securing the drum in operative relation to the reservoir and the wick tubes, a gallery removably mounted about the outer wick tube and having at its bottom an inwardly projecting member, and coöperating means carried by the drum and the gallery for preventing the operation of such securing means when the gallery is inverted.

14. In an oil stove, the combination of a reservoir, an inner and an outer wick tube projecting thereabove, a drum movable toward and from the reservoir, a gallery removably mounted about the outer wick tube and having at its bottom an inwardly projecting member, and coöperating means carried by the drum and the gallery for preventing the drum from being brought into operative relation to the reservoir when the gallery is inverted.

15. In an oil stove, the combination of a

reservoir, a pair of wick tubes projecting thereabove, a drum movable toward and from the reservoir, a pair of locking members for securing the drum in operative relation to the wick tubes and the reservoir, a gallery removably mounted about the outer wick tube, and means whereby the locking members may not be brought into operative relation to each other in the event the gallery is inverted.

16. In an oil stove, the combination of a reservoir, a pair of wick tubes projecting thereabove, a drum movable toward and from the reservoir, a collar carried by the drum, a gallery removably mounted about the outer wick tube and adapted to form with the collar an air distributing device for the exterior of the flame, said collar and gallery being provided with means adapted to interengage to hold the drum out of operative relation to the parts therebeneath when the gallery is inverted.

17. In an oil stove, the combination of a reservoir, a pair of wick tubes projecting thereabove, a drum movable toward and from the reservoir, air controlling means for the exterior of the flame produced above the wick tubes, said air controlling means comprising a collar member carried by the drum, a gallery member removably mounted about the outer wick tube and having an inwardly projected bottom plate, said members being adapted to telescope the one within the other when the gallery member is in proper relation to the collar member, and means preventing such telescoping action when the gallery is inverted, thereby to prevent the drum from occupying a proper relation to the parts therebeneath.

18. In an oil stove, the combination of a reservoir, a pair of wick tubes projecting thereabove, a drum movable toward and from the reservoir, said drum having an annular bottom, a collar depending from the

opening in the drum bottom, a gallery about 45 the outer wick tube, and a telescopic connection between the top of the gallery and the bottom of the collar, the space within the collar and the gallery surrounding the upper end of the outer wick tube being of substantially uniform diameter whereby a wide and free passageway is provided between the wick tube and the surrounding parts for the air entering through the gallery and a substantially air-excluding joint is provided 50 between the top of the gallery and the bottom of the collar notwithstanding variations in the vertical position of the bottom of the collar with reference to the top of the gallery.

19. In an oil stove, the combination of a reservoir, a pair of wick tubes projecting thereabove, a gallery member of substantially uniform diameter extending about the outer wick tube and having its upper end 65 freely spaced therefrom, a drum movable toward and from the reservoir and having an annular bottom, and a collar member depending from the opening in said bottom, said members being provided, the one with 70 a rounded end and the other with a skirt adapted to receive such rounded end, the space within the collar and the gallery surrounding the upper end of the outer wick tube being free and unobstructed whereby a 75 substantially air-excluding joint is provided between the bottom of the skirt and the top of the gallery notwithstanding variations in the vertical positions of the skirt and of such rounded end.

In testimony whereof, we hereunto affix our signatures in the presence of two witnesses.
